US0D1041854S

(12) **United States Design Patent** (10) **Patent No.:** **US D1,041,854 S**
(45) **Date of Patent:** **** Sep. 17, 2024**

(54) **INSOLE**

(71) Applicant: **Hangzhou Muxing Technology Co., Ltd.**, Zhejiang (CN)

(72) Inventor: **Liang Jiang**, Zhejiang (CN)

(73) Assignee: **Hangzhou Muxing Technology Co., Ltd.**, Zhejiang (CN)

(**) Term: **15 Years**

(21) Appl. No.: **29/935,050**

(22) Filed: **Mar. 29, 2024**

(51) LOC (14) Cl. **02-04**

(52) U.S. Cl. **D2/961**
USPC ....

CLAIM

The ornamental design for an insole, as shown and described.

DESCRIPTION

FIG. 1 is a front, right and bottom perspective view of an insole, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a cross-sectional view taken along section line 9-9 in FIG. 3.

The broken line arrow in FIG. 3 forms no part of the claimed design.

1 Claim, 9 Drawing Sheets
